IMPACT-FUSE.

988,610.

Specification of Letters Patent.

Patented Apr. 4, 1911.

Application filed July 28, 1909. Serial No. 510,102.

To all whom it may concern:

Be it known that we, KARL WIESER, residing at Florastrasse 4, and WILHELM SCHWARTZ, residing at Bergstrasse 20, Bredeney, Germany, both subjects of the Emperor of Germany, have invented a certain new and useful Improvement in Impact-Fuses, of which the following is a specification.

10 The present invention relates to impact fuses; and the object of the invention is to provide an impact fuse which is so sensitive that it enters into action even when the projectile, which is provided with the fuse, 15 hits the bag of a balloon.

In the accompanying drawings, Figure 1 is an axial longitudinal section of one embodiment of the invention; Fig. 2 is a top view of Fig. 1; Fig. 3 is a section on line 20 3-3, Fig. 1, looking from above; Fig. 4 is an axial-longitudinal section of a second embodiment of the invention; and Fig. 5 is a top view of Fig. 4.

The embodiment of the invention shown 25 in Figs. 1 to 3 will first be described. The base-plug G, containing the pellet g¹ is screwed into the fuse-body A. The hollow member H, being under influence of the spring h², is slideable and loosely mounted in 30 the fuse-body and carries an ignition-needle h¹. This spring tends to displace the hollow member H in such a manner that the needle h¹ ignites the pellet g¹. The hollow member H is held in the transport-position 35 shown in the drawing through the medium of two retaining levers J which are symmetrically arranged relative to the longitudinal axis of the fuse and which can swing on bolts i¹ which extend transversely to the 40 longitudinal axis of the fuse. The levers J hold the member H in the transport position by means of noses i² which engage beneath a collar h³ on the hollow member. The upper ends of the retaining levers J 45 are provided with noses i², which lie against a collar k¹ on a shank K which is slideably arranged in the fuse-head A¹. This shank carries on its end, projecting outside of the fuse-head, a cross-shaped head k², and rests, 50 during the transport condition of the fuse, with a shoulder k³ against a safety device, which is withdrawn by the action of the centrifugal force on the firing of the gun. This safety device (Fig. 3) consists of several 55 plate-shaped arresting or retaining pieces

F, pivotally mounted and being of such a shape, that each arresting piece in swinging out of the safety position, is still able to hold an adjacent arresting piece for a while in the safety position (see Patent No. 60 982,173). One of the arresting pieces F, which is intended to leave its safety position first, is secured therein by a bolt d¹ (Fig. 3), which is moved away in firing by the inertia, thereby liberating the said arresting-piece. The shank K is preferably made from wood or it may be formed by a hollow body of other light material so that it has only small inertia. The weight of the retaining levers J is distributed in such a manner 70 relative to the axis of oscillation of the levers that the center of gravity of the levers is located between their axis of oscillation and their nose i². After the firing, the safety device F is automatically released; and the 75 shank K is then held in its resting position by means of the friction alone, between the collar k¹ and the noses i², which work like jaws of a vise. This friction is sufficient to balance the resistance presented by the air to 80 the head k² of the shank K during the flight of the projectile, as the friction is relatively great, because the centrifugal force created during the flight of the projectile presses the noses i² against the collar k¹ of the shank 85 K due to the above mentioned distribution of the weight of the locking levers J. If the head k² of the shank K hits the bag of a balloon the shank K moves axially to such an extent that the collar k¹ releases the noses i² 90 of the retaining levers J. Under the action of the centrifugal force, the lower ends of the retaining levers J then swing away from each other to such an extent that the noses i² move out of engagement with the collar k¹ 95 of the hollow member H. The result is that the spring h² comes into action and moves the hollow member H rearwardly so that the pellet is ignited by the needle h¹.

In the embodiment shown in Figs. 4 and 100 5, the pellet m¹ is arranged in a hollow member M which is slideably but non-rotatably arranged in a sleeve A³ screwed into the fuse-body A, the member M being under the action of a spring m². This spring tends to move the pellet m¹ toward the needle h¹, but this movement of the pellet m¹ on the member M is prevented by a safety-device when the fuse is in the transport condition. The safety-device mainly

consists of a ring P arranged on the member M and two retaining pieces Q which are swingingly mounted on bolts q^1 in a recess r^1 provided in a member R which closes the sleeve A² toward the fuse-head. The retaining pieces Q are provided with noses q^2 which engage over lugs p^1 of the ring P; and with other noses q^3 , in the manner of the jaws of a vise, the retaining pieces 10 Q rest against a bolt N carrying the ignition-needle n^1 . This bolt N is of greater diameter than the ignition-needle, and is permanently prevented from moving toward the pellet m^1 by means of a collar n^2 . Over 15 the collar n^2 engages a safety-device F, which corresponds to the safety device for the needle-bolt, described in connection with Figs. 1 and 3, and which can have one of its retaining pieces held in the safety position by means of a bolt in the manner described in connection with Fig. 4. The upper end of the bolt N has a further collar n^3 below which engage noses s^2 of two levers S which are arranged diametrically opposite 20 one another and which can swing in a recess of the fuse-body about the bolts s^1 , which extend transversely to the longitudinal axis of the fuse. The free ends of the levers S carry a ring T (see also Fig. 5) which is of 25 greater diameter than the fuse and which has its front edge formed as a saw. A spring U, which tends to hold the bolt N in the position in which the collar n^2 on the bolt lies against the member R, is arranged 30 between the collar n^3 on the bolt N and a plug a^2 which is screwed into the fuse head. After the shot is fired the safety-device F is automatically released. If the projectile 35 which is provided with the fuse, hits the bag of a balloon the bag is torn to pieces by the toothed edge of the ring T, and the resistance thus created causes the outer ends of the levers S to swing rearwardly and through the medium of the collar n^3 the 40 noses s^2 of the levers S carry the bolt N along against the action of the spring U to such an extent that the needle n^1 becomes located opposite the noses q^3 of the retaining piece Q which formerly were lying against the bolt N. As the needle n^1 is of smaller 45 diameter than the bolt N, the retaining pieces Q are not any longer held against turning and the ring P is therefore not held against axial movement. The result is that 50 the spring m^2 enters into action and moves the hollow member M with the pellet m^1 against the needle n^1 .

Having thus described the invention, what is claimed and desired to be secured by Letters Patent, is:—

1. An impact fuse comprising a fuse-body, a pellet in said body, a part projecting outside of the fuse-body and movable to cause ignition of the pellet, a braking means for holding said movable part against move-

ment with a force only slightly in excess of the air pressure acting upon said part during the flight of the projectile, and a safety device preventing movement of said part by the action of the inertia on firing, said device being adapted to be automatically released after firing. 75

2. An impact fuse comprising a fuse-body, a pellet in said body, a part projecting outside of the fuse-body and movable to cause ignition of the pellet, a braking means for holding said movable part against movement with a force only slightly in excess of the air pressure acting upon said part during the flight of the projectile, and a safety device preventing movement of said part by the action of the inertia on firing, said device being adapted to be automatically released after firing and said movable part being cross-shaped on its projecting end for 80 reducing penetrating effect without increasing air resistance. 85

3. An impact fuse comprising a fuse-body, a pellet in said body, a part projecting outside of the fuse-body and movable to cause ignition of the pellet, a braking means for holding said movable part against movement with a force only slightly in excess of the air pressure acting upon said part during the flight of the projectile, and a safety device preventing movement of said part by the action of the inertia on firing, said device being adapted to be automatically released after firing and said movable part having relatively small specific gravity, whereby 90 its inertia developed in flight may be overcome by contact with a slightly resisting body. 95

4. An impact fuse comprising a fuse-body, a pellet in said body, a part projecting outside of the fuse-body and movable to cause ignition of the pellet, said part being so readily movable that the force required for moving the part is only slightly in excess of the resistance opposed to the part by the air during the flight of the projectile, and a safety-device preventing movement of said part by the action of the inertia on firing, said device being adapted to be automatically released when the projectile commences its 105 flight, the projecting end of said movable part being formed as a serrated ring. 110

5. An impact fuse comprising a fuse-body, a pellet in said body, a part projecting outside of the fuse-body and movable to cause ignition of the pellet, said part being so readily movable that the force required for moving the part is only slightly in excess of the resistance opposed to the part by the air during the flight of the projectile, and a 120 safety-device preventing movement of said part by the action of the inertia on firing, said device being adapted to be automatically released when the projectile commences its 125 flight, and a braking means adapted to 130

be held in effective position by centrifugal force during the flight of the projectile to prevent said movable part from being moved by the resistance of the air.

- 5 6. An impact fuse comprising a part movable to ignite the fuse, a spring tending to effect the movement of said part, means whereby said movable part is held from movement against the action of the spring, 50
 10 a member projecting outside of the fuse-body and movable to cause said means being released, a braking means for holding said movable member against movement with a force only slightly in excess of the air pressure 55
 15 sure acting upon said member during the flight of the projectile, said braking means being held in effective position by the action of said spring, and a safety-device preventing movement of said member by the action 60
 20 of inertia on firing, said device being adapted to be automatically released after firing. 65
 7. An impact fuse comprising a fuse-body, a part movable to ignite the fuse, a spring tending to effect the movement of said part, 70
 25 a readily movable member projecting outside of the fuse-body and adapted to be moved by a force but slightly in excess of the resistance offered to said member by the air during the flight of the projectile, a 75
 30 safety-device preventing movement of said member by the action of the inertia on firing, said device being adapted to be automatically released when the projectile commences its flight, and means whereby the 80
 35 movable part is held from movement against the action of the spring, said means being adapted to be released when said member moves upon encountering a resistance greater than the resistance of the air. 85
 40 8. An impact fuse comprising a fuse-body, a part movable to ignite the fuse, a spring tending to effect the movement of said part, a readily movable member projecting outside of the fuse-body and adapted to be 90
 45 moved by a force but slightly in excess of the

resistance offered to said member by the air during the flight of the projectile, a safety-device preventing movement of said member by the action of the inertia on firing, said device being adapted to be automatically released when the projectile commences its flight, and means whereby the movable part is held from movement against the action of the spring, said means being adapted to be released when said member moves upon encountering a resistance greater than the resistance of the air, said means acting as a brake on said member to prevent the member being moved by the resistance of the air. 55

9. An impact fuse comprising a fuse-body, a part movable to ignite the fuse, a spring tending to effect the movement of said part, a readily movable member projecting outside of the fuse-body and adapted to be moved by a force but slightly in excess of the resistance offered to said member by the air during the flight of the projectile, a safety-device preventing movement of said member by the action of the inertia on firing, said device being adapted to be automatically released when the projectile commences its flight, and means whereby said part is held from movement against the action of the spring, said means being adapted to be released when said member moves upon encountering a resistance greater than the resistance of the air, said means comprising pivoted levers having one end engaging said part and having their other end held by centrifugal force in frictional connection with said member during the flight of the projectile to prevent the member being moved by the resistance of the air. 60
